UNITED STATES PATENT OFFICE.

SPIROS C. MARKATOS, OF NEW YORK, N. Y.

SUPPORTING MEANS FOR DRY ROOMS.

Application filed February 18, 1926. Serial No. 89,204.

This invention appertains to novel means for supporting a hat drying chamber in predetermined relation to a conventional boiler used in hat blocking and cleaning establishments and the primary object of the present invention is the provision of a novel supporting ring upon which the lower edge of the hat drying chamber or room is adapted to rest, with novel means for holding the ring in proper position about the boiler.

Another object of the invention is the provision of novel means for associating a hat drying chamber or room with the upper end of a boiler, the room being provided with a depending skirt or apron for snugly receiving the said boiler and a novel supporting member encircling the boiler upon which the lower edge of the apron or skirt is adapted to rest, whereby the said drying chamber will be held on the boiler in correct position against displacement.

A still further object of the invention is to provide a device of simple and durable construction for holding a hat drying chamber or room in predetermined position upon the upper end of a boiler, which can be placed upon the market at a small cost and incorporated with the boiler and hat drying chamber by an ordinary layman.

With these and other objects in view, the invention consists in the novel construction, arrangement and formation of parts, as will be hereinafter more specifically described, claimed and illustrated in the accompanying drawings, in which drawings:

Figure 1 is a vertical section through the hat drying chamber or room and support therefor, showing the room and support in position on a boiler.

Figure 2 is a top plan view of the support for the room.

Figure 3 is a side elevation of a modified form of novel support.

Figure 4 is a section taken on the line 4—4 of Figure 3 showing the modified form of support.

Figure 5 is a side elevation partly in section of a further modified form of support.

Figure 6 is a top plan view of the support of the type shown in Figure 5, and

Figure 7 is a perspective view of a still further modified form of the support.

Referring to the drawings in detail, wherein similar reference characters designate corresponding parts throughout the several views, the letter A generally indicates

a boiler; B the hat drying chamber or room, and C the novel supporting means for holding the chamber or room B in proper position on top of the boiler A.

The boiler A is of the conventional type of hot water boiler usually heated by gas to generate steam and commonly used in the pressing and steaming and blocking of hats.

The hat drying chamber or room B is of substantially the type shown in my prior Patent 1,493,361 issued to me May 6, 1924, and will not be described in detail, but it is to be noted that the same includes the main body 10 having associated with the lower end thereof the depending annular heat deflecting skirt or apron 11 which is snugly received on the top of the boiler so that heat arising from the boiler will be directed into the body 10. In accordance with this invention the lower end of the skirt or apron 11 is provided with an outstruck right angularly disposed flange 12 having its edge provided with a rolled bead 13, so as to strengthen the said flange and to eliminate sharp cutting edges.

The improved support B for holding the drying room or chamber in place above the upper end of the boiler consists of a supporting ring or band 15 which receives the said boiler. As shown the ring or band is of an annular construction and extends entirely above the said boiler. As clearly shown in Figure 1 of the drawings the band or ring 15 has the flange 12 of the skirt or apron 11 of the drying room resting directly thereon whereby the band will form an efficient support therefor.

A number of preferred means can be utilized for holding the support or band 15 in proper position around the boiler and a number of such supporting means has been shown in the drawings.

In Figures 1 and 2 a plurality of supporting legs 16 are provided, the upper ends of which are placed in facial abutment with the periphery of the said ring or band and secured thereto in any desired way, such as by rivets 17. The lower ends of the standards 16 are provided with laterally extending feet 18 which also can be secured against movement, such as by bolts 19 to the floor or other support. As shown in the drawings, the standards 16 are formed from strap iron, but if preferred, the same can be made out of piping or the like.

In Figures 3 and 4 I have shown another

means of holding the ring or band 15 in the desired position and in this form I provide a bracket 20, which is secured at a point intermediate its ends, such as by rivets 21 to the band or ring 15. The upper end of the bracket is provided with inwardly directed arm 22 which is in turn provided with an attaching foot 23, which is adapted to be placed against a wall or other support and any preferred means, such as a screw 24 can be utilized for connecting the foot to the said wall or support. The lower end of the bracket 20 is provided with a right angularly directed attaching foot 25 which is bolted or otherwise secured to the floor, as at 26. This forms a simple yet efficient means for holding the band or ring in place.

In Figures 5 and 6 I have shown another form of means for holding the band or ring 12 in place which embodies a single supporting bracket or leg 30. This bracket or leg 30 can be formed from strap iron, if preferred, and the upper end thereof is rigidly connected to one side of the band or ring 15 by any desired means, such as rivets 31. The lower end of the leg or bracket 30 is provided with a right angularly extending attaching foot 32 which can be bolted as at 33 to the floor.

In Figure 7 I have shown a still further modified form of means for holding the ring 15 in place and this embodies a wall bracket 35, which is of a substantially inverted U-shape and which extends radially from one side of the band. This wall bracket 35 embodies a straight body portion 36 and depending attaching feet 37 formed on the opposite ends thereof. The inner foot 37 is rigidly connected to the band 12 in any desired way, such as by rivets 38, while the other foot 37 is connected to the wall or other support.

In use of the improved device, the band 12

with the supporting means is slipped over the upper end of the boiler A, until the same reaches the desired point below the upper end of the boiler, after which the supporting means therefor is secured in place. The hat drying chamber or room B is then placed over the top of the boiler with the flange 12 resting on the upper edge of the ring.

It is obvious from the foregoing that the ring can be readily placed in position about the boiler and that the same will form an efficient support for said drying room.

Changes in details may be made without departing from the spirit or scope of this invention, but

What I claim as new is:

1. An attachment for steam boilers comprising a drying chamber arranged above and in axial alignment with the boiler and having a portion encircling and enclosing the boiler, and means for supporting the chamber from the floor and independent of the boiler.

2. An attachment for steam boilers comprising a supporting structure, and a drying chamber slipped over and enclosing the upper end portion of the boiler and resting on said supporting structure.

3. An attachment for steam boilers comprising a supporting structure including a ring for encircling the boiler and spaced therefrom, and a drying chamber including a skirt slipped over the boiler and provided with a flange resting on said ring.

4. A drying attachment for steam boilers comprising an open bottom drying chamber, a skirt depending from the drying chamber for enclosing relation with the boiler, and a frame attached to the floor and separate from and independent of said boilers providing a rest for said skirt.

In testimony whereof I affix my signature.

SPIROS C. MARKATOS.
